UNITED STATES PATENT OFFICE.

BENJAMIN E. ROBINSON, OF SALLYARDS, KANSAS.

FLUID-DISCHARGE MEANS FOR BOTTLES.

Application filed February 21, 1921. Serial No. 446,619.

To all whom it may concern:

Be it known that I, BENJAMIN E. ROBINSON, a citizen of the United States, residing at Sallyards, in the county of Greenwood 5 and State of Kansas, have invented certain new and useful Improvements in Fluid-Discharge Means for Bottles, of which the following is a specification.

This invention relates to fluid discharge 10 means for bottles.

The object of the invention is to provide a simple and efficient bottle closure equipped with means to produce a non-pulsating outflow eliminating the gurgling and bubbling 15 ordinarily incident to the emptying of such receptacles.

Another object is to provide a bottle closure equipped with means for admitting air to the bottle during the escape of its contents, thereby preventing bubbling and the consequent splattering.

With these and other objects in view, the invention consists in certain novel features of construction as hereinafter shown and described and specifically pointed out in the claims.

In the accompanying drawing:

Figure 1 represents a longitudinal section of the upper end of a bottle with this 30 improvement shown applied and in side elevation.

Fig. 2 is a longitudinal section of the device constituting this invention with a portion of the air tube broken off for convenience in illustration, and,

Fig. 3 is a transverse section taken on the line 3—3 of Fig. 2.

It is well known that in pouring liquid contents from a small mouthed receptacle 40 such as a bottle that gurgling, bubbling and splashing of the outgoing contents occurs owing to the entrance of air through the outgoing liquid. It is to overcome this objectionable feature that this device is intended and it is here shown applied to a bottle B having the ordinary reduced mouth M.

The device constituting this invention comprises a hollow tubular shell 1 constructed of any suitable metal, preferably of aluminum or nickel, and is preferably made tapering throughout with its smaller inner end 2 offset inwardly and provided at its base with a shoulder 3 which forms an abutment for a rubber gasket 5 which encircles the reduced inner end of the shell and preferably is of a width corresponding to the

length of this end as is shown clearly in Fig. 2. The outer end or mouth of the shell 1 has a laterally extending flange or bead 4 which is designed to provide a suitable finish 60 and to assist in pouring.

The gasket 5 is of slightly greater thickness than the width of the shoulder 3 so that when applied the perimeter thereof will project slightly beyond that of the main or body portion of the shell 1 as is shown clearly in Fig. 2 to adapt the closure to fit snugly within the mouth M of the bottle to prevent leakage past the closure, the gasket carried end of said shell conforming in shape and size to the cork used to seal the bottle and which is designed to replace said cork for pouring purposes, the cork fitting in the outer portion of the shell, as shown in dotted lines, to close the bottle to protect its contents.

A substantially L-shaped air inlet tube 6 is carried by the shell 1 and has one end thereof located within the shell and secured to the shell at one side wall thereof being 80 preferably cast integral therewith as is shown clearly in Fig. 3. This tube 6 tapers from its outer toward its inner or attached end providing a funnel-like air inlet opening midway the length of the shell 1 or at a point flush with the inner face of the shoulder 3 and which is closed ordinarily by a stopper S of cork or other suitable material, the inner end of the cork resting on the shoulder 3. The tube 6 is of a length sufficient to position its enlarged discharge end 7 adjacent one side wall of the bottle B in connection with which it is to be used as shown in Fig. 1 which constitutes the air space of the bottle when it is turned side-wise in the position for pouring as shown in Fig. 1.

In the use of this device which is primarily intended as a substitute for the sealing stopper, the bottle B which may be a carboy, having been delivered filled with liquid the sealing stopper is removed and the pouring shell 1 is inserted in the mouth thereof, fluid-tight therein with the air inlet pipe 6 arranged as shown, when the bottle is turned down for pouring. The cork S is placed in the mouth of the shell 1 after the desired quantity of liquid has been removed to protect that remaining.

When it is desired to remove the contents 110 of the bottle the stopper S is removed and the bottle turned on one side with the air

inlet tube 6 disposed upwardly as shown in Fig. 1, the air entering the bottle through said tube to permit the contents of the bottle to flow out through the shell 1 without bubbling or gurgling and the incident splashing ordinarily occurring when pouring out the contents of the small mounted receptacle.

The funnel shape of the tube 6 facilitates the entrance of the air in the bottle so that it facilitates the non-splashing discharge thereof.

The preferred embodiment of the invention is disclosed in the drawings and set forth in the specification, but it will be understood that any modifications within the scope of the claimed invention may be made in the construction without departing from the principle of the invention or sacrificing any of its advantages.

What is claimed is:

1. A bottle closure comprising a hollow shell fitting the mouth of the bottle, and an air tube in one piece with the shell and curving toward one side of the bottle in an upward direction and gradually expanding toward that end remote from the shell with the wide end terminating close to the inner wall of the bottle when the latter is substantially horizontal.

2. A bottle closure comprising a hollow shell to fit the mouth of the bottle in connection with which it is used, with a substantially L-shaped air inlet tube having one arm arranged longitudinally of the inner face of the side wall of said shell when the bottle is in a horizontal position, said inlet being integral with the shell and the inner or free end of the tube gradually in-

creasing in diameter toward the air inlet end and constituting a funnel-like termination rising close to the inner wall of the bottle.

3. A bottle closure comprising a hollow tapered tubular shell having its smaller end offset inwardly with a shoulder at its junction with the body of the shell on the outer and inner faces thereof, a rubber gasket encircling the outer face of said end with the inner end abutting said shoulder; and an air inlet pipe arranged on the inner face of the smaller end of the shell and integral therewith with its terminal flush with the shoulder in the shell and the other end curved outwardly and laterally toward the inner wall of the bottle, and a closure for the end of the shell beyond the said air inlet pipe.

4. A closure of the class described, comprising a tapered tubular shell having one end offset inwardly with a shoulder formed at the junction thereof with the body portion, a laterally extending flange at the larger end of the shell and a substantially L-shaped inlet pipe increasing in size from that end entering and integral with the shell to the other end to form a substantially funnel-shaped member, the smaller inner end being arranged at and flush with the reduced portion of the shell and integral therewith, and a removable cork fitting the enlarged outer end of the shell and adapted to abut said shoulder, and a rubber gasket fitting the outer face of the reduced portion of the shell.

In testimony whereof, I affix my signature hereto.

BENJAMIN E. ROBINSON.
